UNITED STATES PATENT OFFICE.

VINCENT BENDIX, OF CHICAGO, ILLINOIS.

ENGINE-STARTER.

1,288,477.

Specification of Letters Patent. Patented Dec. 24, 1918.

Application filed June 18, 1917. Serial No. 175,432.

To all whom it may concern:

Be it known that I, VINCENT BENDIX, a citizen of the United States, residing at Chicago, in the county of Cook and State of Illinois, have invented certain new and useful Improvements in Engine-Starters, of which the following is a specification.

My invention relates to that class of engine starter exemplified in patents heretofore issued to me, for instance, Patent No. 1,125,935, dated January 26, 1915, and No. 1,172,864, dated February 22, 1916, which starter is characterized by a prime mover, such as an electric motor, and a transmission or drive operating on the screw shaft principle for transmitting the power of the motor to be started, such as the fly-wheel thereof.

The object of my invention is to provide a simple, efficient and reliable transmission or drive of the general character described, designed for double reduction, that is, for indirect driving between the armature shaft of the motor and the screw-shaft of the drive.

In the drawing the figure is a sectional elevation of a transmission or drive embodying my invention.

Referring to the selected embodiment of my invention as here illustrated, the electric motor indicated at A has an armature shaft 1 to whose outer end is secured a driving wheel pinion 2 meshing with a driving wheel or gear 3 suitably secured, as by means of a key, to the driving shaft 4 of the drive or transmission.

The armature shaft passes through a plate or bracket 5 which forms the bearing for the inner end of said driving shaft, the outer end thereof having bearings in a casing 6 inclosing the working parts of the drive. This driving shaft is a plain shaft throughout with the exception of its enlarged cylindrical portion 4^a adjacent the gear 3. Upon the outer end portion of the driving shaft is mounted a hollow screw shaft 7 having both a longitudinal and rotary movement with respect to the driving shaft and also a rotary movement therewith. The power of the electric motor is transmitted to the driving shaft 4 through the pinion 2 and gear 3 and

is transmitted from such driving shaft to the screw shaft by a driving means which is here in the form of a yielding driving connection consisting of a coiled spring 8 anchored at one end to the enlargement 4^a of the driving shaft by means of the stud or bolt 9 and at its other end by means of the stud or bolt 10 to the driving head or stop-nut 7^a which may be separate from or integral with the screw shaft. The screw shaft does not extend to the right as far as the bearing of the driving shaft but a space 11 is left to permit of longitudinal movement of the screw shaft on the driving shaft and against the tension of the spring 8, which movement tends to expand such spring.

The driving shaft has a rotary movement only and is held against longitudinal movement (when the screw shaft moves longitudinally) by suitable means such as the shouldered end 4^c abutting the shaft bearing in the casing 6.

Upon the screw shaft is screw-threaded the driving member which is here in the form of a pinion 12 adapted to mesh with a member of the engine to be started, such as the teeth 13^a of the fly-wheel 13.

Describing the operation and starting with the parts in the position shown, when the electric motor is operated the power will be transmitted from the armature shaft through the pinion 2, gear 3, shaft 4 and spring 8 to the screw shaft, with the result that the pinion 12 will be advanced longitudinally of the shaft and into mesh with the fly-wheel teeth. When the pinion is in full mesh and abutting the head 7^a acting as a stop, it will partake of the rotary movements of such shaft and will rotate the fly-wheel. When the engine starts on its own power the pinion 12 will be automatically demeshed and returned to normal position.

In the event that the pinion teeth should abut the fly-wheel teeth end to end and the pinion should thereby be momentarily stopped, the screw shaft will yield longitudinally by moving slightly to the right, in which action such shaft will slide on the driving shaft and its head 7^a will be separated from the shoulder 4^b formed on the driving shaft against which such screw

shaft is normally held with a yielding pressure by means of the driving spring 8. This longitudinal movement of the screw shaft is permitted by the provision of the 5 clearance space 11 and tends to expand the spring 8, which will restore the screw shaft to its normal position when meshing takes place. This momentary stopping of the pinion 12 causes a slight rotation thereof, 10 with the result that the teeth will be brought into register and proper meshing thereby obtained.

I claim:

1. In combination with a driving shaft, a 15 driven gear secured thereto, a screw shaft in the form of a sleeve mounted on the outer end of the driving shaft, a driving member mounted on the sleeve for longitudinal movement thereof and rotary movement therewith, and a driving means associated 20 with the inner end of the driving shaft and connecting between the two shafts and located between the gear and the inner end of the screw shaft.

2. In combination with a driving shaft, a driven gear secured thereto, a screw shaft in the form of a sleeve mounted on the outer end of the driving shaft, a driving member mounted on the sleeve for longitudinal 30 movement thereof and rotary movement therewith, and a yielding driving means associated with the inner end of the driving shaft and connecting between the two shafts and located between the gear and the 35 inner end of the screw shaft.

3. In combination with a driving shaft, a driven gear secured thereto, a screw shaft in the form of a sleeve mounted on the outer end of the driving shaft for longitudinal 40 and rotary movement thereon and rotary movement therewith, a driving member mounted on the sleeve for longitudinal movement thereof and rotary movement therewith, and a yielding driving means 45 associated with the inner end of the driving shaft and connecting between the two shafts and located between the gear and screw shaft, said means being arranged to permit of said longitudinal movement of the screw 50 shaft.

4. In combination with a driving shaft, a driven gear secured thereto, a screw shaft in the form of a sleeve mounted on the outer end of the driving shaft, a driving member 55 mounted on the sleeve for longitudinal movement thereof and rotary movement therewith, and a driving spring associated with the inner end of the driving shaft and connecting between the two shafts and 60 located between the gear and screw shaft.

5. In combination with a driving shaft having an enlarged portion forming an annular shoulder, a driven gear secured to such shaft, a screwshaft in the form of a sleeve 65 mounted on the driving shaft and normally

abutting said shoulder, a driving member mounted on the sleeve for longitudinal movement thereof and rotary movement therewith, and a yielding driving connection between the two shafts.

6. In combination with a driving shaft having an enlarged portion forming an annular shoulder, a driven gear secured to such shaft, a screwshaft in the form of a sleeve mounted on the driving shaft and normally 70 abutting said shoulder, a driving member mounted on the sleeve for longitudinal movement thereof and rotary movement therewith, and a yielding driving connection between the two shafts in the form of a 75 spring encircling said enlarged portion and anchored at its ends to the two shafts respectively.

7. In combination with a driving shaft having an enlarged portion forming an annular shoulder, a driven gear secured to such shaft, a screw shaft in the form of a sleeve mounted on the driving shaft and normally 80 abutting said shoulder, a driving member mounted on the sleeve for longitudinal movement thereof and rotary movement therewith, and a yielding driving connection between the two shafts in the form of a 85 spring encircling said enlarged portion and anchored at its ends to the two shafts respectively, said screwshaft being capable of longitudinal movement on the driving shaft and away from said shoulder and against the tension of the spring.

8. In combination with a driving shaft 100 having an enlarged portion forming an annular shoulder, a driven gear secured to such shaft, a screw shaft in the form of a sleeve mounted on the driving shaft and normally abutting said shoulder, a driving member 105 mounted on the sleeve for longitudinal movement thereof and rotary movement therewith, and a yielding driving connection between the two shafts in the form of a coiled spring encircling said enlarged portion and anchored at its ends to the two shafts respectively, said screw shaft being 110 capable of longitudinal movement on the driving shaft and tending to expand the spring.

9. In combination with a rotatable driving shaft having end bearings, a driven gear secured to the shaft, a screw shaft in the form of a sleeve mounted on the driving shaft between its bearings, a driving member mounted on the sleeve for longitudinal movement thereof and rotary movement therewith, and a yielding driving means located adjacent said gear and connecting between the two shafts, said driving shaft 115 having an enlarged portion adjacent said gear against which portion the screw shaft 120 abuts.

10. In combination with a driving shaft, a driven gear secured thereto, a screw-shaft in 125

the form of a sleeve mounted on the outer end of the driving shaft for longitudinal and rotary movement thereon and rotary movement therewith, a driving member 5 mounted on the sleeve for longitudinal movement thereof and rotary movement therewith, means for preventing longitudi- nal movement of the driving shaft when the screw shaft moves longitudinally, and a yielding driving means associated with the 10 inner end of the driving shaft and connecting between the two shafts and located between the gear and screw shaft.

VINCENT BENDIX.
